UNITED STATES PATENT OFFICE.

ELDEN P. LAMB, OF CAMDEN, MAINE, ASSIGNOR TO CAMDEN ANCHOR-ROCKLAND MACHINE CO., OF ROCKLAND, MAINE.

VAPORIZER FOR HYDROCARBON-ENGINES.

964,657.

Specification of Letters Patent. Patented July 19, 1910.

Application filed August 30, 1909. Serial No. 115,239.

To all whom it may concern:

Be it known that I, ELDEN P. LAMB, a citizen of the United States, residing at Camden, Maine, have invented certain new and useful Improvements in Vaporizers for Hydrocarbon-Engines, of which the following is a specification.

My present invention relates to improvements in charge forming devices or vaporizers for hydrocarbon engines, and comprises the novel construction and arrangement and combination of parts hereinafter described and particularly set forth in the appended claims.

15. A vaporizer constructed in accordance with my invention is illustrated in the accompanying drawings in which:

Figure 1 is a side elevation of the complete vaporizer; Fig. 2 is a central vertical section of the same; Fig. 3 is a horizontal section on line 3—3 of Fig. 1; Fig. 4 is a horizontal section on line 4—4 of Fig. 1; Fig. 5 is a sectional detail of the float controlled inlet valve; Fig. 6 is a detached detail view; Fig. 7 is a plan view; and Fig. 8 is a section on line 8—8 of Fig. 3. Fig. 9 is a detail view of the sight tube for indicating the hydrocarbon level.

The main casing or body of the vaporizer 30 consists of a casting 1 having inner and outer concentric walls 1^a and 1^b, and a bottom 2. The annular space 4 between the walls 1^a and 1^b constitutes the fuel chamber in which the hydrocarbon is maintained at the proper 35 level by a float 5 carried by a rocking lever 6 pivoted in an extension 7 of the chamber, and having its end forked to engage the stem of a valve 8 which controls the fuel inlet 9. The valve stem is provided with collars 10 above and below the fork of the lever, and the upper end of the stem is projected through a screw cap 11 and serves for priming purposes. From the fuel chamber 4 the hydrocarbon passes through passages 45 4^a to a heating chamber or space 12 formed between two cones 13 and 14. The upper cone 13 is preferably formed as an integral part of the main casing, as shown, and carries, at its upper end, the atomizing opening 50 for delivering the jet or spray of hydrocarbon into the combustion chamber in the form of vapor, the walls of this opening being preferably flared upwardly, as indicated at 15, to coöperate with the needle valve 16 55 which regulates the amount of hydrocarbon

delivered under the suction of the engine. The lower cone 14 is held by a screw plug 17 fitting a corresponding opening in the bottom of the main casing, and provides a closed interior heating chamber 18 within the cone, into which a heating medium, as, for instance, the exhaust gases from the engine, are conducted through a pipe or tube 19, preferably of copper and from which they pass by way of annular tubular extension 20 and branch or angle pipe 21 to the main exhaust pipe, (not shown).

From the construction thus described, it will be seen that the hydrocarbon, in an exceedingly thin film or layer, is subjected to the heat of the hot gases within the cone, the heat being readily transferred by the thin wall of the cone 14, and it will also be noticed that the heat is applied to the hydrocarbon prior to and right up to the point when it is discharged into the mixing chamber, whereby it is in condition to make an efficient mixture.

As fully explained in the specification of Letters Patent No. 776,406, granted Nov. 24, 1907, for an earlier invention of mine, it is desirable, to secure the best results, to provide for the admission of air in varying quantities, both above and below the needle valve or point of delivery of the hydrocarbon into the mixing chamber, and I provide, in the present vaporizer, improved means for accomplishing this purpose.

The cover 22 of the vaporizer is of annular form, and from the edge of its central opening depends an annular wall 23, which forms, between the wall 1^b and the central mixing chamber, an annular air chamber 24. This wall is provided with an upper row of ports or openings 25, and a lower row 95 of ports 26, the former being above the level of the point of discharge of the hydrocarbon into the mixing chamber, and the latter below, and the two sets of openings being staggered in relation to each other, as clearly shown in Fig. 6.

Within the annular wall 23 is located a cylinder 27, which is provided with two sets of similarly staggered ports, and it will be readily seen that by oscillating the cylinder, either the upper or the lower rows of ports may be more or less brought into alignment.

The throttle is indicated at 28, comprising simply a rotatable plate having openings 28^a adapted to be brought more or less into

alinement with similar openings 29^a of a stationary plate 29, the throttle being operated through a tubular spindle 30 provided with a hand lever or other suitable operating means, such as shown at 31, which may be provided with a spring pressed dog 32 riding over a notched quadrant 33 to hold the lever in any position to which it may be adjusted.

10 The cylinder which constitutes the air controlling valve, as above described, is operated by means of a tubular spindle 30 through which the spindle 34 passes, and which carries a hand lever 35 which has a 15 spring pressed dog 36 engaging a notched quadrant carried by or connected with the hand lever 31 of the throttle, so that the air valve may be independently adjusted to any desired degree, but, after adjustment, will 20 be moved in unison with the throttle.

The parts are so arranged that for starting purposes and with a partially closed throttle air is drawn through the lower openings to secure a rich mixture, while as 25 the throttle is more widely opened the lower openings are closed and the upper openings opened, which produces a less rich mixture as described in my prior patent hereinbefore referred to.

30 The needle valve passes through the tubular spindle 34 and is provided, on its upper end, with a thumb nut threaded upon a boss of the hand lever 35, so as to enable rotary motion of the nut upon the boss to effect vertical adjustment of the needle valve, the nut being held against rotation independently of the boss by a spring pressed dog 36.

I prefer to provide means by which either warm or cold air or a mixture may be supplied. To effect this, I provide an inlet 37 to the air chamber for warm air, the air being taken from around the exhaust pipe (not shown) or any other source of heat, while I admit cold air through the lower air chamber 38, formed by the depending wall 3, the air passing up through suitable ports 39 into chamber 24, and the admission of air to chamber 38 being controlled by a suitable valve plate 40.

50 A vaporizer as thus constructed may be used for light hydrocarbons such as gasoline or the heavier kerosene, and to enable it to be thus used I connect to the lower end of the plug 9^a a valve casing 41 having inlets from opposite sides, as indicated at 42 and 43, to which gasoline and kerosene may be respectively piped from any suitable sources (not shown) one or the other being put in communication with the fuel chamber 60 by a three way valve 44.

Sometimes the float which controls the fuel level needs adjustment. This is ordinarily a difficult matter to determine, and in order to simplify this, I provide a sight tube 45 by which the height of liquid may

be determined from mere observation from the exterior, and the degree of adjustment needed, if any, noted. This adjustment is accomplished by a hinged pin 45' upon which the float lever 6 is pivoted, which hinged pin has projections journaled in the walls of the chamber, the hinged pin and projections being eccentric to each other so that rotation of the hinged pin will effect the vertical adjustment of the float lever 6. 75 Provision is made to operate this pin from outside of the chamber wall 1^a which in turn raises or lowers the float, thereby regulating the level of the hydrocarbon. Such provision may consist merely in a slot in the 80 end of the pin to receive a screw driver or like device. By means of this eccentric pin capable of being operated from the outside, the fuel level can be changed and located through the glass without the carburetor 85 being taken down, which is quite an important feature.

Having thus described my invention what I claim is:—

1. A vaporizer for internal combustion engines comprising a mixing chamber having means for supplying air thereto, a pair of members of substantially cone shape spaced to admit a film of hydrocarbon therebetween, the upper of said members having an atomizing opening for injecting the combustible fluid into said mixing chamber, and means for admitting heating fluid to the interior of the lower member, substantially as described. 100

2. A vaporizer for internal combustion engines comprising a mixing chamber having means for supplying air thereto, a pair of members of substantially cone shape spaced to admit a film of hydrocarbon therebetween, the upper of said members having an atomizing opening for injecting the combustible fluid into said mixing chamber, a removable plate carrying the lower member and closing the bottom thereof, and induction and eduction pipes for heating fluid leading to the space within said lower member, substantially as described. 105

3. A vaporizer for internal combustion engines comprising a mixing chamber having suitable air admitting ports, upper and lower elements in the lower part of said mixing chamber spaced to provide a chamber for receiving a thin film of hydrocarbon, said upper element having an opening discharging into the mixing chamber, a needle valve extending downwardly through said mixing chamber and co-operating with said opening, and means for heating the lower element, substantially as described. 115

4. In a vaporizer for internal combustion engines, the combination with the mixing chamber, and a feed nozzle therein, of a cylindrical casing within said chamber and surrounding said nozzle, and having radi- 120

ally arranged air openings above and below said nozzle, an air valve for regulating said openings, a throttle valve above the chamber and controlling the exit of combustible fluid therefrom, and means whereby said valves may be moved in unison and also adjusted independently of each other, substantially as described.

5. In a vaporizer for internal combustion engines, the combination with the mixing chamber and a feed nozzle therein, of a cylindrical casing within said chamber and surrounding said nozzle, and having radi-
ally arranged air openings above and below
10 said nozzle, an air valve for regulating said openings, a throttle valve above the chamber and controlling the exit of combustible fluid therefrom, a tubular stem for said throttle valve extending through the top of the
15 vaporizer and provided with a suitable operating handle, a stem for the air valve extending through the stem of the throttle valve and having a similar handle, and a device normally connecting said parts for
20

causing them to move in unison, substantially as described. 25

6. In a vaporizer, the combination with the mixing chamber and feed nozzle therein, of a cylindrical casing having air inlet ports leading to said chamber above and below the nozzle, an oscillatory air valve controlling said ports, an oscillatory throttle valve controlling the exit of the combustible mixture from said chamber, tubular stems for said throttle valve and air valve arranged 30 the one within the other and extending through the top of the vaporizer, a needle valve for controlling the feed nozzle having a stem extending through the innermost tubular stem, and means for operating all 35 said stems, substantially as described.

In testimony whereof, I affix my signature in presence of two witnesses.

ELDEN P. LAMB.
